UNITED STATES PATENT OFFICE.

BENJAMIN F. McGUINNESS, OF SAUNDERSVILLE, MASSACHUSETTS, ASSIGNOR TO CROMPTON & KNOWLES LOOM WORKS, OF WORCESTER, MASSACHUSETTS, A CORPORATION OF MASSACHUSETTS.

LOOM-SHUTTLE.

1,268,136.

Specification of Letters Patent. Patented June 4, 1918.

Application filed March 7, 1917. Serial No. 153,016.

To all whom it may concern:

Be it known that I, BENJAMIN F. McGUINNESS, a citizen of the United States, residing at Saundersville, town of Grafton, in the county of Worcester and State of Massachusetts, have invented a new and useful Loom-Shuttle, of which the following is a specification.

This invention relates to a loom shuttle 10 particularly designed for use in automatic weft replenishing looms of the type in which fresh weft carriers are automatically inserted to renew the weft supply.

In such loom shuttles it is essential that the thread shall enter the shuttle eye easily and quickly, and it is also essential that displacement of the thread shall thereafter be prevented. Owing to the twist, the thread frequently assumes seemingly impossible positions while running and not infrequently the thread thereby escapes from shuttle eyes of the usual type. Such escape of the thread is of course objectionable and produces unsatisfactory results.

It is the principal object of my present invention to provide a shuttle eye in which the thread is positively retained in the eye after it is automatically inserted therein. A further object of my invention is to provide a shuttle eye in which the threading operation may be performed in a most reliable manner and in which the possibility of misthreads is correspondingly reduced. An important feature of my invention also relates to the provision of means for cutting the outgoing thread in the shuttle eye as the substantially exhausted weft carrier is ejected from the shuttle. Suitable actuating mechanism is provided for the movable parts, operated in timed relation to the weft replenishing or transfer mechanism. My invention also relates to arrangements and combinations of parts which will be herein-after described and more particularly pointed out in the appended claims.

The preferred form of my invention is shown in the drawings in which—

Figure 1 is a top plan view of a portion of a shuttle with my invention embodied therein;

Fig. 2 is a side elevation of the parts shown in Fig. 1, the shuttle being cut away to show the structure of the shuttle eye;

Figs. 3, 4, 5 and 6 are transverse sectional

views taken along the lines 3—3, 4—4, and 55 5—5 of Fig. 2, and the line 6—6 of Fig. 1, and

Fig. 7 is a side elevation of the portion of the shuttle shown in Fig. 1.

Referring to the drawings, I have shown 60 a portion of a shuttle 10 in which my improved shuttle eye is mounted. The shuttle eye comprises a body member 11 firmly secured in a recess in the shuttle 10 by means of a stud 12 (Fig. 4) extending through 65 an opening in the member and threaded into a nut 13 secured in a recess in the side of the shuttle. A thread passage 14 is formed in the body member 11, said passage extending longitudinally of the shuttle and communicating at its forward end with a transverse passage formed between the member 11 and the shuttle body 10, and communicating with a slotted sleeve 15 through which the thread leaves the shuttle. 70

At a point adjacent the entrance of the thread passage 14 I have provided a closure comprising an arm 16 pivoted at 17 to the body member 11 and adapted to normally close the open upper side of the passage 14. 80 The arm 16 is provided with segment teeth forming a partial pinion positioned for engagement by rack teeth 18 formed on the side of a plunger 19. This plunger is vertically slidable in the body member 11 and 85 normally projects above the upper surface thereof, being yieldingly retained in this position by a flat spring 20 secured to the upper end of the plunger and engaging the upper surface of the member 11. The spring 90 20 thus normally holds the plunger in raised position and holds the arm 16 in the position shown in Fig. 3.

For actuating the plunger 19 I provide an engaging member 21 which may be formed 95 on the transceiver of the weft replenishing mechanism or may be operated in timed relation with said mechanism. It is essential merely that the engaging member 21 shall depress the plunger 19 as the fresh bobbin is 100 inserted in the shuttle. Such depression of the plunger raises the arm 16 and permits the convenient insertion of the thread from the incoming weft carrier. After the thread is inserted the plunger is allowed to rise, depressing the arm 16 and closing the upper side of the passage 14 so that escape of the thread is thereafter impossible. 105

It is frequently desirable to sever the thread attached to the outgoing weft carrier at the time when the transfer is made, and for this purpose I have provided a movable knife blade 22 secured to a shaft 23 extending longitudinally through bearings in the body member 11 and provided at its rear end with a segment pinion 24 engaging a second rack 25 on the lower end of the plunger 19. The movable knife blade 22 co-acts with a second knife blade 26 which is fixed to the member 11.

With this construction it will be evident that the descent of the plunger 19 will 15 press the blade 22 to sever the thread from the outgoing bobbin at the same time that it raises the arm 16 to permit the insertion of the incoming thread. A coil spring 27 may be provided, surrounding the shaft 23 and 20 having one end secured to the pinion 24. The opposite end of the spring is secured to some fixed member such as the knife blade 26 and the spring co-operates with the spring 20 previously described to raise the plunger 25 and maintain the knife blade 22 in inoperative position. Reference to the drawings will show that the spring 20 and the upper end of the plunger 19 do not project above the upper face of the shuttle 10 even in their 30 raised positions.

Having thus described my invention, it will be evident that changes and modifications may be made therein by those skilled in the art without departing from the spirit 35 and scope of the invention as set forth in the claims, and I do not wish to be otherwise limited to the details herein disclosed, but what I do claim is:—

1. In a loom, a shuttle having a shuttle 40 eye formed with a thread passage therein, a closure for said passage, a plunger vertically movable in said shuttle eye, a rack and pinion connection between said plunger and said closure, transfer mechanism, and a 45 member movable with said transfer mecha-

nism effective to engage and actuate said plunger to move said closure to inoperative position.

2. In a loom, a shuttle having a shuttle eye formed with a thread passage therein, an 50 arm pivoted in said shuttle eye and normally closing the upper side of said passage, a spring effective to retain said arm yieldingly in normal position, transfer mechanism, and means operative in timed relation therewith 55 to move said arm to inoperative position, said means comprising a pinion movable with said arm, a plunger slideable in said shuttle eye and having rack teeth thereon engaging said pinion, a member positioned to 60 engage and depress the upper end of said plunger to thereby raise said arm, and means to move said member in timed relation to the transfer mechanism.

3. In a loom, a shuttle having a shuttle 65 eye formed with a thread passage therein, a closure for said passage, means to actuate said closure, a thread cutter in said shuttle eye, and connections between said closure and said cutter whereby said cutter is actu- 70 ated in timed relation to said closure.

4. In a loom, transfer mechanism, a shuttle having a shuttle eye formed with a thread passage therein, a closure for said passage, a thread cutter in said shuttle, and a member 75 movably mounted in said shuttle and operatively connected to said closure and to said cutter, said member being actuated in timed relation with said transfer mechanism.

5. In a loom, transfer mechanism, a shuttle having a shuttle eye formed with a thread 80 passage therein, a closure for said passage, a thread cutter in said shuttle, a plunger, rack and pinion connections from said plunger to said closure and to said cutter, and means 85 associated with said transfer mechanism for actuating said plunger.

In testimony whereof I have hereunto affixed my signature.

BENJAMIN F. McGUINNESS.
